TELEVISION SCREEN

Fritz Schröter, Max Knoll, and Bernhard Bartels,
 Berlin, Germany, assignors to Telefunken Ge-
 sellschaft für Drahtlose Telegraphie m. b. H.
 Berlin, Germany, a corporation of Germany

Application January 9, 1937, Serial No. 119,715.
 In Germany December 23, 1935

6 Claims. (Cl. 250—27.5)

This invention relates broadly to television scanning apparatus, and more particularly to a grid screen of the type used in cathode ray image scanners of the form wherein the electronic charge image is formed on one side of the grid screen and the cathode ray scanning device operates and impinges on the other side of the grid screen. Such screens have, in the prior art, been termed double side grid screens and broadly are well known.

It has been usual in the prior art to form the screen of a metallic supporting structure which is multi-apertured, that is to say, is formed in a net or sieve-like form. Through each of the apertures, a conducting element is passed, and on one extremity of the conducting element is deposited a photoelectric material, and the other extremity is subject to the electron bombardment from the cathode ray. It is, therefore, obvious that these conducting elements must be insulated both from each other and from the net or sieve-like metallic body which acts as the supporting structure.

Heretofore it has been difficult in the manufacture of these screens to provide adequate insulating means between the conducting elements hereinbefore referred to, which carry a photoelectric deposit, in such a manner that the screens could be made practicable from a commercial standpoint.

It is, therefore, one of the objects of this invention to provide a grid screen of such a nature as to be comparatively easy to manufacture and a screen which will have adequate and desirable insulating means for electrically separating the conducting elements passing through the apertures therein.

Our invention will be best understood by reference to the figure which illustrates one embodiment.

Referring to the figure, the metallic supporting structure 10 may consist of a material whose oxide is an electric insulator as, for instance, tungsten, molybdenum, aluminum or tantalum. The aluminum is especially desirable since its oxide has a high resistance not only to mechanical stresses which may take place when the conducting elements are inserted, but due to the fact that its oxide forms a very good insulator. For forming the oxide on aluminum, it is usually preferable to produce the insulating layer by means of electrolytic oxidation. Tantalum possesses the advantage that its oxide when formed in a layer or by oxidation, has a very high

ohmic resistance and its adhesion to the metal itself is very great.

Adhering to the metallic support 10 is a layer of the oxide of the metal which is used, the said oxide being formed in well known manners as, for instance, by electrolytic oxidation or direct oxidation. The oxide layer 11 will then cover the outer surface of the metal 10 and will line the apertures 12 through which the conducting elements 13 pass. The conducting element 13 may 10 in general be in the form of a pin, one of whose ends is formed of a frusto-conical section, and on the outer face of this section is deposited a layer of photoelectric material 14. The pin then passes through the aperture and on its opposite 18 side is subject to electronic bombardment on the surface 15.

For the purposes of clarity, there has been illustrated only one section of the screen greatly enlarged. It will be appreciated that these conducting pins are sufficiently great in number so that the outer surface of the frusto-conical section which holds the photoelectric material will be sufficiently close to that of the next pin so as to form a close fitting photoelectric mosaic. 20 25

It is possible also to provide the insulating surface on the sieve or net-shaped metal body by chemical or electrolytic methods using a metal other than the supporting sieve whose oxide is an insulator as, for instance, barium, caesium or magnesium. These substances may be evaporated in a vacuum and deposited on the metal net-shaped support, and by subsequent oxidation, a successful and desirable insulating layer is formed. 30 35

What we claim is:

1. A cathode ray tube screen comprising a multi-apertured planar metallic supporting structure, a uniform layer of the oxide of said metal formed integral with said metallic support in the 40 apertures therein, a plurality of conducting members each held in one of the apertures of the support structure, said members being of larger cross-sectional area at one end thereof than the other end thereof, and a deposit of photoelectric 45 material on the enlarged areas of each of said members.

2. A cathode ray tube screen comprising a multi-apertured planar tungsten supporting structure, a uniform layer of tungsten oxide 50 formed integral with said support, a plurality of conducting members each held in one of the apertures of said supporting structure, said members being of a pin formation and having one end thereof of greater cross-sectional area than the 55

other end thereof, and a deposit of photoelectric material on the enlarged areas of each of said members.

3. A cathode ray tube screen comprising a multi-apertured aluminum supporting structure, a uniform layer of planar aluminum oxide formed integral with said support, a plurality of conducting members each held in one of the apertures of said supporting structure, said members being of a pin formation and having one end thereof of greater cross-sectional area than the other end thereof, and a deposit of photoelectric material on the enlarged areas of each of said members.

4. A cathode ray tube screen comprising a multi-apertured molybdenum supporting structure, a layer of uniform planar molybdenum oxide formed integral with said support, a plurality of conducting members each held in one of the apertures of said supporting structure, said members being of a pin formation and having one end thereof of greater cross-sectional area than the other end thereof, and a deposit of photoelectric material on the enlarged areas of each of said members.

5. A cathode ray tube screen comprising a

multi-apertured metallic supporting structure, a uniform layer of a planar metallic oxide formed integral with said metallic support and in the apertures therein, a plurality of conducting members each held in one of the apertures of the supporting structure, said members being of a pin formation and having one end thereof of greater cross-sectional area than the other end thereof, and a deposit of photoelectric material on the enlarged areas of each of said members.

6. The method of forming a double mosaic screen structure which comprises the steps of producing a planar metallic electrode, perforating said electrode with a plurality of minute apertures therein according to a predetermined regular pattern, oxidizing the surface of the electrode including the apertured areas therein to provide an insulating layer filling the insulating apertured areas with electrically conducting material having a greater exposed areas on one side of the aperture than on the other side, and photo-sensitizing the enlarged area of the conducting material.
